ELLIPSOGRAPH

Arthur E. Randles, Redwood City, Calif.

Application December 29, 1952, Serial No. 328,422

2 Claims. (Cl. 33—31)

1

This invention relates to improvements in ellipsographs.

The invention provides an improved design suited for manufacture of the instrument from standard round and flat stock with the minimum of machining operations. The improved instrument is simple to assemble and adjust, easy to pre-set for ellipses of various sizes and operates smoothly due to freedom from binding of, and undue friction between, its operating parts, a disadvantage inherent in many forms of conventional ellipsographs. The new design of the instrument permits the drawing of very accurate figures, up to sizes which are quite large considering the compact size of the instrument and affords a wide range of adjustment. In one extreme adjustment circles can be drawn, in another extreme adjustment the instrument draws straight lines. In intermediate positions the instrument draws ellipses, the long and short axis of which may be conveniently pre-set by a rather simple adjustment on the instrument.

These and various other objects, features and advantages of the invention will appear more fully from the detailed description which follows, accompanied by drawings, showing for the purpose of illustration, a preferred embodiment of the invention. The invention also resides in certain new and original features of construction and a combination of elements hereinafter set forth and claimed.

Although the characteristic features of this invention, which are believed to be novel, will be particularly pointed out in the claims appended hereto, the invention itself, its objects and advantages, and the manner in which it may be carried out, may be better understood by referring to the following description taken in connection with the accompanying drawings forming a part of it in which:

Fig. 1 is a perspective view of the instrument in operating position;

Fig. 2 is a perspective view of the instrument turned upside down; and

Fig. 3 is a perspective detailed view of a preferred form of mounting for the scribe.

In the following description, and in the claims, various details will be identified by specific names for convenience. The names, however, are intended to be as generic in their application as the art will permit. Among the terms employed, the element for drawing the figure proper is collectively referred to as a scribe or scribing means, it being understood that it may be a pencil, pen, stylus, engraving tool, or any other means used for a similar purpose.

2

In the drawings accompanying, and forming part of, this specification, certain specific disclosure of the invention is made for the purpose of explanation of broader aspects of the invention, but it is understood that the details may be modified in various respects, without departure from the principles of the invention, and that the invention may be applied to other structures than the one specifically shown.

10 Referring to the drawings, the ellipsograph comprises a frame 11. The frame proper is preferably constructed from a pair of parallel bars 12 and 13, substantially of C-shape when viewed in elevation. The ends 14, 15, 16 and 17 of the C constitute legs and are provided with the usual point inserts 18, 19, 20 and 21, held in place by set screws 22, 23, 24 and 25. The eight portions 26 and 27 of the C are substantially straight and parallel and constitute a pair of tracks 28 and 29.

A pair of parallel second bars 30 and 31 extend between the eight portions 26 and 27 of the C bars 12 and 13. The second bars are preferably threaded at the ends, screwed into corresponding tapped holes 32 in the bars 12 and 13. Lock nuts visible at 33 and 34 serve to tighten the connection between the second bars 30, 31 and the first bars 12 and 13. The second bars 30 and 31 extend at right angles to the first bars 12 and 13 and also constitute a pair of tracks for a purpose which will presently be described.

A first carriage 35 is movable along the tracks 28 and 29 of the instrument. This carriage is preferably substantially I-shaped. The ends of 35, the I, 36 and 37 are blocks which straddle the bars 12 and 13 and are slidable along the tracks 28 and 29. The portion 38 of the first carriage intermediate the ends 36 and 37 is preferably elevated, and is conveniently constructed from a piece of flat stock screwed to the blocks 36 and 37 at 39 and 40.

A further carriage 41 is mounted on the tracks 30 and 31 for movement transverse with regard to, and underneath, the first carriage 35. For this purpose the carriage 41 has a bore 42 therethrough, through which the bar 31 extends, and the other end of the carriage is slotted, or otherwise machined, to engage and slide along the bar 30, as shown at 43.

50 A first crank is rotatably mounted on the first carriage 35. This crank consists of a shaft portion 44 rotatable in the intermediate portion 38 of the first carriage. A manually operable crank operator, or crank arm 45 extends through a bore 55 in the crank shaft 44. Its length may conveniently be adjusted by longitudinal movement of

the arm relatively to the shaft portion 44 and subsequent tightening of a set screw 46.

The second carriage 41 likewise is provided with a crank whose shaft portion 47 extends through, and is rotatable on, the body of the carriage 41. The top portion of the crank shaft 47 in the illustrated embodiment is milled out at 48 to receive a bar 49 which forms the crank arm for the second crank. The bar or arm may be provided with a graduated scale 50 for adjustment relatively to a mark 51 on the shaft portion 47. A set screw 52 serves to arrest the bar in adjusted position.

One end of the bar or arm 49 has non-rotative engagement with the shaft 44 of the first crank. As shown particularly in Fig. 2, this is conveniently accomplished by milling a flat surface 53 on the end of the crank shaft 44. A set screw 54 bears against the flat surface and prevents the crank shaft 44 from turning with regard to the bar 49.

From the foregoing it is apparent that the distance between the axis of the first crank shaft 44 and the axis of the second crank shaft 47 may be adjusted by sliding the bar 49 longitudinally within the milled out portion 48 of the crank shaft 47. The scale 50 aids in this adjustment, which is the adjustment of the instrument for an ellipse having a long axis of predetermined length. The bar 49 is set in adjusted position by tightening the set screw 52. The milled out portion 48 of the crank 47 is so dimensioned that the crank shaft 44 may be moved into co-axial position with the crank shaft 47. If this is done, the instrument draws a circle.

The bottom end of the crank shaft 47 is likewise milled out at 55 to accommodate an arm 56. The arm 56 also may be provided with a graduated scale 57 readable on a mark 58 on the crank shaft 47. The scale 57 indicates the distance of the scribe 59 from the axis of the shaft 47 and permits pre-setting of the instrument for an ellipse having a short axis of predetermined length. After adjustment the bar 56 is arrested by a set screw 60.

The scribe 59 may be a pencil, pen, stylus, engraving tool, or any other means for outlining the desired curve, and is preferably mounted in such a way as to be movable towards, and away from, the drafting surface on which the instrument rests. Provision is made in this connection to urge the scribing means towards the drafting surface. The bias force may be exerted by gravity, but in the illustrated embodiment is derived from a flat spring 61 secured to the arm 56 at 62. The end of the flat spring carries a socket 63 for the scribe. In the illustrated embodiment the scribe is shown as having the form of a pencil point 64 passing through a bushing 65. It is arrested in adjusted position by a set screw 66. It is apparent that the spring pressure with which the point 64 bears against the drafting surface can be adjusted simply by projecting the point 64 more or less from the bushing 65 and then clamping the point 64 by means of the set screw 66.

The milled passage 55 within the crank shaft 47 is so dimensioned that the scribe 59 can be brought into co-axial position with the crank shaft 47. In this position the instrument draws a straight line.

The use of the apparatus is evident from the foregoing description. The instrument is set for the figure to be drawn, for example an ellipse, by adjusting the length of the arm 49 of the second

crank 47 and adjusting the length of the scribe arm 56. The scales 50 and 57 aid in this adjustment. Rotation of the operating crank or handle 45 then causes the desired outline to be drawn on the surface on which the instrument rests.

It is apparent that the scribe arm sweeps the area between the four legs of the instrument. The distance of this arm from the drafting surface is very short. This feature contributes to accuracy of the drawn outline. Great accuracy of the instrument is further due to the provision of relatively widely spaced parallel tracks for both the first and the second carriage. This arrangement prevents binding of the movable parts, reduces friction and results in great accuracy without requiring unduly close tolerances in the machining of the parts. For example, the play between the first carriage and its tracks may be adjusted by rotating the second bars 30 and 31, it being understood that each bar has a right-handed thread at one end and a left-handed thread at the other. Turning of the bars thus results in a change in the spacing of the tracks 28 and 29 straddled by the first carriage 35.

25 The second carriage 41 had a long bore 42 within which the bar 31 is guided. The axis of the second crank 47 lies close to the bore 42, whereby smooth operation of the second carriage is insured.

30 The entire instrument is compact and relatively small, yet it permits relatively large figures to be drawn since the scribe may sweep the entire area between the four legs 14, 15, 16 and 17.

35 The instrument is conveniently adjustable for the drawing of predominantly large or predominantly small ellipses. In the position shown in Fig. 1, the scribe 59 is on the same side with regard to the shaft 47 as the shaft 44. Thus 40 adjusted, the instrument draws ellipses, the long axis of which is parallel to the tracks 28 and 29.

If very large ellipses are to be drawn, the arm 56 is removed from its slot and reinserted from the opposite side, so that the scribe 59 is 45 on the opposite side of the shaft 47 with regard to the shaft 44. In this position, the instrument draws ellipses, the long axis of which are parallel to the track 30 and 31. The scribe may sweep the entire space between the legs, corresponding 50 to the short axis, and move considerable distances beyond the bars 12 and 13, thereby permitting unusually large ellipses to be drawn.

What is claimed is:

1. An ellipsograph comprising, in combination, 55 a pair of parallel first bars, substantially of C-shape in elevation, the ends of the C constituting legs, the bight of the C being substantially straight and constituting first tracks; a pair of parallel second bars secured to, and extending between, said first bars at right angles to said first tracks, said second bars spacing said first bars apart and constituting second tracks; a substantially I-shaped first carriage, the ends of the I straddling, and riding on, said first bars, 60 the portion of the I intermediate the said ends being elevated with respect to the points of engagement of the ends with said first bars; a first crank shaft rotatably mounted in said elevated portion of said first carriage; a manually operable first crank operator secured to said first crank shaft above said elevated portion for turning said first crank shaft; a second carriage slidably mounted on said second bars for movement at right angles with regard to, and underneath 65 the elevated portion of, said first carriage; a

second crank shaft mounted in said second carriage; a crank arm extending through said second crank shaft for longitudinal adjustment with regard to the said second crank, the end of the crank arm being non-rotatively secured to said first crank shaft underneath said elevated portion, the longitudinal adjustment of said crank arm permitting variation of the distance between said crank shafts; a scribe arm extending through said second crank shaft underneath said second carriage for longitudinal adjustment with regard to said second crank shaft, said scribe arm extending substantially at right angles to said second crank shaft and sweeping an area below said second bars and between said legs; and scribing means mounted on said scribe arm.

2. An ellipsograph comprising, in combination, a pair of parallel first bars, substantially of C-shape in elevation, the ends of the C constituting legs, the bight of the C being substantially straight and constituting first tracks; a pair of parallel second bars secured to, and extending between, said first bars at right angles to said first tracks, said second bars spacing said first bars apart and constituting second tracks; a substantially I-shaped first carriage, the ends of the I straddling, and riding on, said first bars, the portion of the I intermediate the said ends being elevated with respect to the points of engagement of the ends with said first bars; a first crank shaft rotatably mounted in said elevated portion of said first carriage; a manually operable first crank operator secured to said first crank shaft above said elevated portion for turning said first crank shaft; a second carriage slidably mounted on said second bars for movement between said second bars and at right angles with

regard to, and underneath the elevated portion of, said first carriage; a second crank shaft mounted in said second carriage at a point between said second bars and immediately adjacent 5 one of said second bars; a crank arm extending through said second crank shaft for longitudinal adjustment with regard to the said second crank, the end of the crank arm being non-rotatively secured to said first crank shaft underneath said elevated portion, the longitudinal adjustment of said crank arm permitting variation of the distance between said crank shafts; a scribe arm extending through said second crank shaft underneath said second carriage for longitudinal 10 adjustment with regard to said second crank shaft, said scribe arm extending substantially at right angles to said second crank shaft and sweeping an area below said second bars and between said legs; a scribing arm extension; a flat spring securing said extension to said scribing arm with freedom for the extension to move towards, and away from, the plane of said second bars; and scribing means mounted on said extension.
